ABSTRACT: A joint for joining parts of an aerosol-type dispensing device having a cap member and a valve assembly with a valve member. The joint has a male joint means on one of said members and a female joint means on the other of said members. The male joint means has a radially extending portion and the female joint means has a radially extending portion. The radially extending portion of the male joint means is engaged over the radially extending portion of the female joint means between the radially extending portion of the female joint means and the member on which the female joint means is positioned, and the radially extending portion of the female joint means is engaged over the radially extending portion of the male joint means between the radially extending portion of the male joint means and the member on which the male joint means is positioned. The cap member and the valve body member are thus tightly connected.

JOINT FOR JOINING PARTS OF AN AEROSOL-TYPE DISPENSER

This invention relates to an aerosol dispenser, and more particularly relates to an aerosol dispenser of the type in which the product to be dispensed is contained in an outer product container separate from the propellant, the propellant being contained in an inner cartridge within the outer container.

Heretofore there have been proposals for providing such an aerosol dispenser having a plug valve assembly which is attached to the underside of a cap for the outer or product container. The plug valve assembly includes a valve body which contains a valve mechanism that during dispensing controls the flow of the propellant and the product to be dispensed. The usual form of dispenser has the outer container, the cap, and the valve body formed of one type of plastic. This plastic is usually a somewhat resilient and easily molded plastic. The conventional manner of attaching the valve body to the underside of the cap is to provide a depending portion from the underside of the cap and a mating portion on the top of the valve body. These two portions are brought together, and a conventional plastic joining step is carried out, such as spin welding, sonic welding, or heat sealing. Such steps, however, involve providing special joining equipment, such as welding apparatus, in order to carry out these steps. Moreover, since these steps are carried out by an operator of an apparatus of an appropriate type, the joints are not always uniformly good, one operator sometimes making better or worse joints than another operator. Also, where a heat-sealing step is used, the heat from the joint can affect the dimensional tolerances of the adjacent parts to a greater or lesser degree, again depending to some extent on the skill of the operator.

There are also occasions when it would be desirable to have the cap and the valve body of different plastic materials, for example when the valve body is integrally joined to a propellant cartridge of a plastic which is impervious to the propellant, while the cap is of a different plastic which need not be impervious to the propellant. However, when the parts are of different plastic materials, they cannot usually be joined by any of the conventional plastic-joining steps, such as spin welding or sonic welding.

It is an object of the present invention to provide a construction of the cap and the valve body for an aerosol dispenser of the type described above, in which a simple mechanical joint is provided between these parts.

It is a further object of the present invention to provide an aerosol dispenser with a cap and valve body which are easily joined by a simple manipulative movement which does not involve a plastic-joining step, such as welding.

These objects are accomplished by providing an aerosol dispenser assembly in which the cap has a mating member depending from the underside of the cap, which mating member forms part of a mechanical joint, and the valve body of the plug valve assembly has the other mating member of the mechanical joint on the top thereof. One of the mating members is a ring-shaped member having a projecting flange thereon, and the other mating member has a projecting annular collar or a plurality of fingers having projections thereon which engage over the flange on the annular ring-shaped member.

With this construction, it is merely necessary to force the cap and the annular valve body toward each other. The part having the annular ring-shaped member with the projecting flange will deform sufficiently to enable the annular collar to pass the annular flange, and snap over the annular flange into engagement therewith.

The invention will now be described in greater detail in connection with the accompanying drawings, in which:

FIG. 1 is a sectional elevational view of the upper portion of an aerosol dispenser showing the mechanical connection;

FIG. 2 is an enlarged cross-sectional view of a portion of an alternative embodiment of the mechanical connection according to the invention; and

FIG. 3 is an enlarged cross-sectional view of a portion of a further embodiment of the mechanical connection according to the invention.

The aerosol dispenser according to the invention comprises an outer container 1 for containing a product to be dispensed, which product is in a fluent form, for example liquid or a finely divided powder. A cap 3 is mounted on the outer container 1 at the upper edge 4 of the outer container. The cap 3 has an aperture 3a in the center thereof through which a valve stem 5, to be described below, projects.

Depending from the under surface of the cap 3 is one member of the mechanical joint according to the present invention. In the embodiment of FIG. 1, this member is a female joint means in the shape of an annular ring 6 having an inwardly projecting flange 6a on the lower end thereof. The upper surface of the annular flange 6a is preferably inclined slightly back toward the cap 3, i.e. upwardly from the annular ring.

Positioned below the cap 3 is a valve body 7 having a hollow interior 8, and having an opening through the bottom thereof with an annular gasket 9 therein. Around the top of the valve body 7 is a mating member of the mechanical joint according to the invention. In the embodiment of FIG. 1, this mating member is a male joint means in the form of an annular collar 10 which projects substantially radially outwardly and preferably has the lower surface inclined slightly back toward the valve body, i.e. downwardly from the annular body 7. The annular collar 10 is tightly engaged over the inwardly projecting flange 6a on the annular ring 6.

The valve body 7 can be made of one type of plastic, and the cap 3 and depending annular ring 6 can be made of the same or a different type of plastic.

In order to assemble the valve body and the cap, all that is necessary is to press the valve body 7 upwardly into the annular ring 6. The annular collar 10 will spread the annular ring 6 sufficiently so that annular collar 10 will pass the inwardly projecting flange 6a, and the flange 6a will snap under the annular collar 10 to hold the valve body tightly to the cap 3.

The male joint means of the connection, i.e. the annular collar 10 on the valve body 7, can be placed instead on the cap, so that the annular ring depending from the cap has an outwardly projecting annular collar thereon, and the female joint means is placed on the valve body 7 so that the inwardly extending annular flange 6a is on the valve body.

The remaining elements of the aerosol dispenser comprise a depending annular flange 11 depending from the valve body 7, to the lower end of which is attached a propellant cartridge 13 having therein a propellant 14 which normally is under high pressure in liquid form. In the form of the aerosol dispenser shown, the upper edge of the propellant cartridge 13 is complementary in shape to the lower edge of the downwardly and outwardly flared portion 12 on the depending flange 11, and the parts are joined integrally with each other, for example by welding. However, any other conventional connection can be used, such as bending the metal wall of a metal cartridge over the edge of the outwardly flared portion with a seal of some sort between the metal and plastic of the flared portion.

Clamped between the annular crown 7a around the top of the valve body 7 and a downwardly extending projection 3b around the opening 3a in the cap 3 is a ring gasket 15 which acts as a low-pressure obturator for the admission of air to the product container 1 from outside the dispenser.

The valve stem 5 extends through the hollow interior 8 of the valve body 7 and the opening 3a in the cap 3 opens into hollow interior 8. A valve actuator in the form of a pushbutton 16 is mounted on the top end of the valve stem 5 and contains a nozzle insert 17 having a venturi-type spray nozzle therein. Nozzle insert 17 is set into a cavity in the pushbutton 16. The opening 8 in the bottom of the body 7 opens into the interior of cartridge 13.

A flange 19 on valve stem 5 is urged upwardly by a spring 20 around valve stem 5. The lower end of spring 20 is held in a cup-shaped portion of a retaining ring 21 in the bottom of the hollow interior 8, and the retaining ring 21 is urged against the

high-pressure gasket 9 in the bottom of the hollow interior 8. The retaining ring 21 is held in the bottom of the hollow interior 8 by an annular ring-retaining projection 22 projecting into the hollow interior 8 at the upper end of retaining ring 21. The spring acts to press the flange 13 upwardly so that the flexible lip of gasket 6 held between a truncated cone-shaped seat 13a on flange 13, cambered as shown, and the annular projection 3b around the edge of opening 3a in cap 3. This provides a tight closure of the hollow interior 8 with respect to opening 3a and a tight closure of a passage 7b which extends through the annular ring 6 into the space beneath cap 3. In the raised position shown in FIG. 1, there is a space between inner edge of gasket 15 and the tapered lower end of a depending wall 13 on the pushbutton. This opens into the channels 24 described hereinafter.

The pushbutton 16 which caps the valve stem 5 has two coaxial sockets at the base thereof, an outer socket defined by depending wall 23 and which fits tightly around valve stem 5, and an inner socket which receives the reduced diameter upper end 5a of stem 5. The extent to which the sockets can be forced along valve stem 5 is limited by an annular shoulder 5c at the base of the upper end 5a of stem 5. Stem 5 has splines 25 along the outside thereof defining between them channels 24 along the outside of the stem 5. The channels open out of the stem through apertures 26. The upper end of dip tube 27 opens into the hollow interior 8 and is force fitted in a bore 27a in body 7 for conducting material to be dispensed into the hollow interior 8.

Valve stem 5 is made in one piece, for example by molding, and has an axial bore 28 with a conical head 29 closing the lower end thereof.

At the lower end of the stem 5 is a neck portion having a reduced diameter portion 29a in which is a plurality of lateral openings 30 which, when the valve stem is in the raised position, are obturated by the inner peripheral edge of gasket 9. In the lowered position of the stem 5, the gasket 9 flexes to open openings 30 to admit propellant to the axial bore 28.

In operation, when the parts of the dispenser are in the position as shown in FIG. 1, the high-pressure propellant in the cartridge 13 is obturated by gasket 9, and the interior of the container 1 is obturated by gasket 15, thus sealing both the product and the propellant from the outer atmosphere 30.

Depression of the pushbutton 16 flexes both these gaskets, opening the openings 30 to admit propellant to the bore 28 of the stem, thus aspirating the product to be dispensed through the dip tube 27, the hollow interior 8 past the now downwardly flexed gasket 15, through the passage 24 and through the apertures in the nozzle insert 17.

An alternative form of the joint is shown in FIG. 2. Depending from the cap 3 is a male joint means in the form of an annular ring 32 having a wider portion 31a and a narrower inner portion 32b. The portion of the ring 32 between the larger part 32a and the narrower part 32b is beveled outwardly. Projecting radially outwardly from the lower end of the narrower inner portion 32b is an annular collar 33. The annular collar preferably has a blunt pointed lower end 33a, both edges of which are beveled and the upper surface of the annular collar 33 is inclined upwardly from the inner portion 32b.

On the upper end of the valve body 7 is a female joint means in the form of a plurality of upwardly projecting fingers 34, each having at the upper end thereof radially inwardly projecting portions 34a. The under surfaces are preferably inclined downwardly from the fingers. Preferably the upper ends of the finger 34 are beveled inwardly of the valve body 7 so that they are complementary in shape to the outwardly beveled portion of ring 32.

The fingers 34 are preferably spaced equidistantly around the periphery of the annular body 7, while the ring 32 is a complete ring.

Since fingers 34 are provided, the fingers will be sufficiently resiliently movable in the radial direction to pass over the annular collar 33 and snap over this collar and into engagement therewith. The inwardly beveled upper ends of the fingers will

be wedged outwardly by the beveled portion of the lower end of the annular collar 33, thus assisting in the spreading of the fingers 34.

It will, of course, be understood that the relative positions of the collar and the fingers could be reversed, i.e. the ring could be radially outwardly of the fingers and have the collar projecting inwardly and the projecting portions of the fingers could project outwardly.

A further embodiment is shown in FIG. 3, the embodiment being generally upside down from that shown in FIG. 2, namely the male joint means of the joint is on the valve body 7 while the female joint means is on the cap 3. The cap 3 has an annular ring 30 depending therefrom, and depending from the lower portion of the ring 30 is the female joint means in the form of a plurality of fingers 41 having inwardly projecting portions 41a thereon. The inner edge of the inwardly projecting portions 41a is inwardly beveled at 41b.

The valve body 7 has on the upper portion thereof a male joint member in the form of an outwardly projecting annular collar 42, and the surface of the valve body above the annular collar 42 is beveled outwardly as shown at 43.

Because of the provision of the fingers 41, when the valve body 7 is urged upwardly against the fingers 41, the beveled surface 43 will urge the fingers 41 outwardly as it slides along the beveled edge 41b. This will spread the fingers sufficiently to enable the annular collar 42 to snap over the inwardly projecting portion 41a into engagement with the member 40. It will, of course be understood that, as with the embodiment of FIG. 2, the relative positions of the collar and the fingers could be reversed with the collar projecting inwardly over the outwardly projecting portions on the fingers.

It will thus be seen that there has been provided a mechanical joint between the cap and the valve body which is simple, yet is such that the valve body and the cap can be made of different plastics which cannot be joined by such conventional methods as welding, heat sealing, etc. The engagement between the parts is sufficiently tight to hold the valve body and the remainder of the plug valve assembly firmly to the cap. The arrangement also makes easy the positioning of the low-pressure obturator gasket 15 between the parts of the joint, and the joint will hold this obturator firmly in position during the operation of the dispensing device. Since the connection is purely mechanical, the variations in the quality of welded or heat-sealed joints introduced by the operators are eliminated, and no heat is used which will tend to destroy the dimensional tolerances of the various parts.

I claim:

1. A joint for joining parts of an aerosol-type dispensing device having a cap member and a valve assembly with a valve body member, said joint comprising a male joint means on one of said members and a female joint means on the other of said members, one of said joint means being an annular ring having a radially extending flange and the other joint means being a plurality of fingers each having a radially extending projection with the radially extending flange of the one joint means engaged over the radially extending projections on the other joint means between the radially extending projections on the other joint means and the member on which the other joint means is positioned, and the radially extending projections on the other joint means being engaged over the radially extending flange on the one joint means between the radially extending flange of the one joint means and the member on which the one joint means is positioned, whereby the cap member and the valve body member are tightly connected.

2. A joint as claimed in claim 1 in which the male joint means is on the cap and the female joint means is on the valve body.

3. A joint as claimed in claim 2 in which said male joint means is the one joint means and the radially extending flange is an outwardly extending flange on the lower end of the annular ring, and said female joint means is the other joint means and the radially extending projections are inwardly extending projections on the upper ends of the fingers.

4. A joint as claimed in claim 2 in which said male joint means is the other joint means and the radially extending projections are outwardly extending projections on the lower ends of the fingers, and said female joint means is the one joint means and the radially extending flange is an inwardly extending flange on the upper end of the annular ring.

5. A joint as claimed in claim 1 in which the female joint means is on the cap and the male joint means is on the valve body.

6. A joint as claimed in claim 5 in which said male joint means is the one joint means and the radially extending flange

is an outwardly extending flange on the upper end of the annular ring, and said female joint means is the other joint means and the radially extending projections are inwardly extending projections on the lower ends of the fingers.

5 7. A joint as claimed in claim 5 in which said male joint means is the other joint means and the radially extending projections are outwardly extending projections on the upper ends of the fingers, and said female joint means is the one joint means and the radially extending flange is an inwardly extending flange on the lower end of the annular ring.
